RAZOR

Justin Simon, Brooklyn, and Richard S. Temko,
New York, N. Y.

Application June 9, 1945, Serial No. 598,443

6 Claims. (Cl. 30—61)

1

This invention relates generally to razors and more particularly to razors of the type having a relatively stiff blade either of the single or double edge type. In razors of this character the blade is supported upon a platform and a cover element both clamps the blade upon the platform and advances it against detents which position it with respect to the guard.

In razors of this class as heretofore constructed the cover element was moved into position by a member which was longitudinally reciprocated by a screw thread in the handle. The operation of this prior art device necessitated holding the handle of the razor in one hand and holding the cover element actuating member and twisting the same with the other hand.

It is desirable for many reasons that the razor be fully manipulatable with only one hand, and among these is that when a razor is operated with only one hand, the user's other hand may remove the dull blade from the blade supporting platform and may replace it with a new sharp blade. This feature is of particular importance where the blade changing operation is performed while the user is standing upon an unsteady surface as for example, in a railway car, and is of particular advantage where the new sharp blades are placed in the razor by the action of an ejector type magazine disclosed in my copending application for Letters Patent, Serial No. 598,442, filed June 9, 1945.

It is therefore among the objects of the present invention to provide razor structure wherein a blade may be clamped between a blade supporting platform and a cover element and wherein the cover element may be completely controlled by the user's fingers while the razor handle is carried by the same fingers of the same hand.

Another object herein lies in the provision of a razor construction wherein the cover element in the clamping position thereof properly engages the blade so as to carry the same in the correct position with respect to the detents and guard.

A further object herein lies in the provision of a razor having locking means whereby the cover element is prevented from undesirably opening while the razor is in use as a shaving instrument.

Another object herein lies in the provision of razor structure having the foregoing desirable operating characteristics and which is of a relatively simple and fool proof nature so that the same may have a long, trouble-free useful life.

A still further object herein lies in the provision of the structure of the character described having a minimum of operating parts so that the same

2

may be manufactured in large scale at low cost and have a consequential wide distribution sale and use.

A feature of the invention lies in the fact that when the cover is opened by only one hand manipulation of the razor, a dull blade may be conveniently and simply dropped by tilting, inverting or flicking the razor (the momentum of the blade throwing it off the platform).

These objects and other incidental ends and advantages will more fully appear in the progress of this disclosure and be pointed out in the appended claims.

In the drawings in which similar reference characters designate corresponding parts throughout the several views:

Figure 1 is an enlarged fragmentary vertical sectional view of a razor showing an embodiment of the invention. In this figure the cover element is shown in an open position thereof.

Figure 2 is an enlarged fragmentary vertical sectional view of the razor shown in Figure 1 with the parts in a closed and latched position.

Figure 3 is a fragmentary front elevational view as seen from the left of Figure 1.

Figure 4 is a fragmentary sectional view as seen from the plane 4—4 of Figure 1.

Figure 5 is a fragmentary side elevational view of an alternate form of latched tip and rack member with the parts arranged and corresponding generally with the arrangement shown in Figure 2.

In accordance with the invention the razor 10 includes generally a handle 11, a blade supporting platform 12, a cover element 13, a rack member 14, a rack spring 15, a shiftable latch 16, a latch spring 17 and a motion transmitting element 18.

The blade platform 12 is preferably generally 40 of rectangular configuration and is adapted to support, for example, a well known type of single edge safety razor blade 19, which may be provided with a rear edge reinforcement 20. The blade 19 may, if desired, as is well known, be of 45 the relatively stiff double edge type. The blade 19 has a central slot within which the projection 21 is slidably engageable so that the blade 19 may have a limited movement toward and away from the guard 22. Disposed at the outward corners 50 of the guard 22 are a pair of detents 23.

Journalled in the rear portion of the platform 12 and disposed transversely of the razor 10 is the motion transmitting element 18. The central portion of the element 18 is provided with a series 55 of spaced longitudinal grooves to form the pinion

portion 24. The outer ends of the element 18 have fixed radial arms 25 at the outer ends of which the cover 13 is pivotally attached. The cover 13 includes a top wall 26, an angular wall 27, a rear wall 28 and a pair of side walls 29. At the juncture of the top wall with each of the side walls there are provided a pair of blade shifting lugs 30. These lugs are adapted to engage correspondingly positioned indentations in the side edges of the razor blade (not shown) and to extend down to the oppositely disposed slots 31 in the platform 12. The upper portion of the handle is provided with a pair of bosses 32 which engage corresponding openings (not shown) in the platform 12 and by means of which the handle 11 may be assembled with said platform. The central upper portion of the handle 10 includes a guideway 33 within which the rack member 14 is slidably mounted for motion forwardly and rearwardly of the razor. The rack member is of irregular shape best seen in Figures 1 and 4 of the drawings and includes a spring enclosing recess 34, a latch receiving notch 35 and a series of transversely arranged rack teeth 36 and a finger engaging tab 37. The rack teeth 36 are in engagement with the pinion portion 24 in such manner that when the pinion is in engagement with the rearmost teeth, the rack member 14 is in its forwardmost position and the rear wall 28 engages the portion 38 at the upper part of the handle 11. Extending downwardly from the lower surface of the platform 12 is a rear spring support 39 which may have a boss 40 about which the rearmost convolutions of the spring 15 are engaged.

The handle 10 is provided with an axial bore 41 within which is disposed the latch spring 17. The latch 16 includes a notch engagement tip 42, a body member 43 having a forwardly projecting actuating member 44. The actuating member 44 extends forwardly through the slot 45 which slot communicates with the bore 41. The lower end of the body 43 may have a pin 46 penetrating the spring 17.

The notch 35 and the tip 42 are so positioned with respect to each other that the tip 42 may enter said notch and seat therein when the cover 13 is in its closed or fully seated position.

Operation of the present razor is a simple and convenient matter. Assuming the parts to be in the position shown in Figure 2 and that the blade 19 is due for replacement, the razor may be grasped in the right hand with the fingers of said hand encircling the portion 47 of the handle 11. The thumb of the user engages the actuating member 44 and moves the same downwardly as viewed in Figure 2, thereby compressing the spring 17, until the tip 42 disengages the notch 35. The expansive pressure of the spring 15 will move the rack member 14 forwardly to the position shown in Figure 1 which in turn rotates the element 18, the arms 25 swinging the cover 26 up and back until the rear wall 28 engages the portion 38. At this stage a flick of the wrist will dislodge the blade 19 without the necessity of handling the same, and the blade may be thrown from the platform 14 into any suitable container. Next, the new blade corresponding to the blade 19 is placed or dropped upon the platform 12 by a manual operation or from a magazine respectively. Now the finger engaging tab is pressed rearwardly by the thumb of the user which closes the cover element by a reversal of the previously described operation, and when the cover element is in its fully seated position, the tip 42 seats

within the notch 35 under the expansive pressure of the spring 17 returning the parts to the position shown in Figure 2.

Turning now to the alternate form of the rack member shown in Figure 5, for the purpose of avoiding unnecessary repetition, parts corresponding to the first form of rack member are given the same reference characters with the prefix "1." The principal difference in the alternate form of Figure 5 lies in the fact that the rear surface 150 of the notch 135 is disposed in a plane which slopes inwardly from the longitudinal axis of the latch 116 and the rear surface 151 of the tip 142 is arranged in a corresponding plane. The length of the latch 116 is such that the terminal surface 152 is spaced from the surface 153 when the cover element 26 is in its fully closed position, compressing the blade 19 by virtue of this structure, and of the fact that the notch 135 is large enough at the forward margin thereof not to contact the forward surface of the tip 142. The tip 142 has a wedging action under the expansive pressure of the spring 17 to constantly urge the cover element 26 to press against the blade 19.

We wish it to be understood that we do not desire to be limited to the exact details of construction shown and described, for obvious modifications will occur to a person skilled in the art.

We claim:

1. In a razor having a blade platform, a handle and a movable cover adapted to engage a blade between itself and said platform, means to actuate said cover comprising: a motion transmitting element connected to the cover; a member movably disposed with respect to said platform and engaging said motion transmitting element whereby when the movable member is in a first position thereof the cover is disengaged with respect to said platform, and in a second position thereof the cover is in an engaged position with respect to said platform; resilient means urging said movable member to the first position thereof; and latch means to retain the movable member as moved to a position closing said cover.

2. In a razor having a blade platform, a handle and a movable cover adapted to engage a blade between itself and said platform, means to actuate said cover comprising: a motion transmitting element connected to the cover; a member slidably disposed with respect to said platform and engaging said motion transmitting element whereby when the slidable member is in a first position thereof, the cover is disengaged with respect to said platform, and in a second position thereof the cover is in an engaged position with respect to said platform; and resilient means urging said slidable member to the first position thereof, said slidable member having a notch; and a movable latch engageable with said notch when said slidable member is in a predetermined position thereof.

3. In a razor having a blade platform, a handle and a movable cover adapted to engage a blade between itself and said platform, means to actuate said cover comprising: a motion transmitting element connected to the cover; a member slidably disposed with respect to said platform and engaging said motion transmitting element whereby when the slidable member is in a first position thereof, the cover is disengaged with respect to said platform, and in a second position thereof the cover is in an engaged position with respect to said platform; and resilient means urging said slidable member to the first position

thereof, said slidable member having a notch; and a movable latch engageable with said notch when said slidable member is in a predetermined position thereof; and resilient means urging said latch in the general direction of the shiftable member.

4. In a razor having a blade platform and a movable cover adapted to engage a blade between itself and said platform, a cover actuating mechanism comprising: a pair of spaced levers radially mounted on an axle at the ends thereof; said cover being pivotally mounted on the ends of said levers; a pinion on said axle; a slidably mounted rack engaging said pinion; resilient means to urge the rack in a direction to open said cover; and latch means to retain the rack as moved to a position closing said cover.

5. In a razor having a blade platform, a handle and a movable cover adapted to engage a blade between itself and said platform, means to actuate said cover comprising: a motion transmitting element connected to said cover; a member movably disposed with respect to said platform and engaging said motion transmitting element whereby when the movable member is in the first position thereof the cover is disengaged with respect to said platform, and in a second position thereof the cover is in an engaged position with respect to said platform; resilient means urging said movable member to the first position thereof; and latch means acting in the engaged position thereof to retain said movable member in the

5 second position thereof, said latch means including a resilient member urging the latch means to a position of engagement, whereby when the movable member is in a predetermined position, engagement of the latch member therewith takes place automatically.

6. In a razor having a blade platform, and a movable cover adapted to engage a blade between itself and said platform, a cover actuating mechanism, comprising: an axle journalled on said platform, said axle having a pinion; a pair of spaced levers, one radially mounted on each of the ends of the axle; said cover being pivotally mounted on the outer ends of said levers; a slidably mounted rack engaging said pinion, said rack having an operating trigger; resilient means to urge the rack in a direction to open said cover; and latch means to retain the rack as moved to a position closing said cover, said latch having 10 an operating handle in juxtaposition with said trigger.
